[57] CLAIM

The ornamental design for a hot air grill, as shown and described.

DESCRIPTION

FIG. 1 is a front perspective view of a hot air grill showing my new design and comprising a foldable base and removable transparent split shell.

FIG. 2 is a top perspective view thereof.

FIG. 3 is a left side perspective view thereof.

FIG. 4 is a right side perspective view thereof.

FIG. 5 is a back perspective view thereof.

FIG. 6 is a perspective view of the base shown in folded condition with the shell removed, the sides not shown in FIG. 6 being seen in FIGS. 3 and 5.

FIG. 7 is a bottom perspective view thereof.

FIG. 8 is a top perspective view of a modification thereof, and

FIG. 9 is a perspective view of the modification shown in FIG. 8, the modification being otherwise as shown in FIGS. 1 to 7.

FIG. 1

FIG. 2

FIG. 3

FIG. 4

FIG. 5

FIG. 6

FIG. 7

FIG. 8

FIG. 9
